SPOON WITH A MUSICAL DEVICE

Taizo Ishida, 14 of 2, Tokiwa 4, Urawa-shi,
Saitamaken, Japan

Filed May 22, 1969, Ser. No. 17,287

Claims priority, application Japan Feb. 20, 1969

Term of patent 14 years

Int. Cl. D21—02

U.S. Cl. D34—15

FIG. 1

FIG. 2

FIG. 1 is a front, top and left side perspective view of a musical spoon or similar article showing my new design; and

FIG. 2 is a front elevational view of FIG. 1, those sides of the handle not seen, being substantially identical; while the bottom is plain, flat and unornamented.

I claim:

The ornamental design for a spoon with a musical device, as shown.
